FIG. 1 is a side elevational view of a jug showing my new design, wherein the handle continues in the same line as the shoulder and then angles downwardly to the body; and wherein the finish is forward of the axial center; and

FIG. 2 is a side elevational view of a jug showing my new design wherein the handle curves downwardly from the shoulder to the body; and wherein the finish is centrally located; and

FIG. 3 is a top plan view of the jug shown in FIG. 2. This application is a division of my co-pending application S.N. 69,802, filed April 2, 1962, which application is a continuation-in-part of application S.N. 68,412, filed January 22, 1962, and now abandoned.

I claim:

The ornamental design for a jug or similar article, as shown and described.
